[57] **CLAIM**

The ornamental design for a bracket for supporting mounting bar on vehicle, as shown and described.

DESCRIPTION

FIG. 1 is a top plan view showing my new design for a bracket for supporting mounting bar on vehicle;

FIG. 2 is a front elevational view thereof;

FIG. 3 is a rear elevational view thereof;

FIG. 4 is a bottom plan view thereof; and

FIG. 5 is a side elevational view thereof it being understood that the broken lines are for illustrative purposes only and form no part of the claimed design.

The side opposite to that shown in FIG. 5 is the mirror image thereof.

FIG. 1

FIG. 2

FIG. 3

FIG. 4

FIG. 5
